UNITED STATES PATENT OFFICE.

HARRY H. GOLDSTEIN, OF HARTFORD, CONNECTICUT.

VENDING-RECEPTACLE.

1,078,346.

Specification of Letters Patent

Patented Nov. 11, 1913.

Application filed September 22, 1912. Serial No. 722,786.

To all whom it may concern:

Be it known that I, HARRY H. GOLDSTEIN, a citizen of the United States, and a resident of Hartford, in the county of Hartford and 5 State of Connecticut, have invented a new and Improved Vending-Receptacle, of which the following is a specification.

My invention relates to the class of devices above named and an object of my invention, among others, is to produce a device of this class that shall be compact and extremely simple in construction and operation.

One form of device embodying the invention and in the construction and use of which the object above set out, as well as others, may be attained is illustrated in the accompanying drawings, in which—

Figure 1 is a view in central vertical section through a vending receptacle embodying my invention, the packages, coin and coin receiving foot being shown in full. Fig. 2 is a view in vertical section on the plane denoted by the dotted line 2—2 of Fig. 1. Fig. 3 is a view in horizontal section on the plane denoted by dotted line 3—3 of Fig. 1. Fig. 4 is a detail perspective view showing the shelf and its prong for supporting the articles.

30 In the accompanying drawings the numeral 5 denotes a casing of any suitable form and composed of any desired material, as shown herein this being rectangular in shape, and having an opening at the front. A vending lever 6 is pivotally mounted on the back wall of the casing on a pivot 7, and a guard lever 8 having a guard 9 is also pivotally mounted on this back wall of the casing and engages the 40 vending lever by a pin and slot connection, as shown in dotted line in Fig. 1. A spring 10 may be employed to hold the parts in normal position of rest. The guard 9 projects at an angle from the guard lever toward the 45 front of the receptacle and is of a length to so close the coin slot 11 that a coin cannot be placed therein. A coin receiving foot 12 is located at the lower end of the vending lever and this also projects from the lever 50 at an angle toward the front of the receptacle.

A door 13 closes the opening at the front of the casing and walls 14 forming a package receiver are secured to and project from this door toward the back of the casing. Each of these walls is provided with a lip

15 to retain the packages in the receiver formed by the door, walls and lips as above described. One of these walls 14 has an egress opening 16 at its lower end, and a shelf 17 secured to the receiver supports the articles therein. This shelf 17 extends entirely across the receiver from the front to the rear, as shown in Fig. 2, and it also has a projection or prong 18 extending, as to 65 its width, a slight distance only from the door but entirely across the receiver from side to side, this prong being of such width that it will not interfere with the movement of a coin to eject a package from the 70 receiver. One of the lips 15 is provided with an inturned part forming a rest 20 upon which one end of the packages are supported, as shown in Fig. 1 of the drawing, this rest also being so disposed that it 75 will not interfere with movement of the coin 19 as herein above explained. A wall 21 also projects from the door 13 at such distance from one of the walls 14 that it forms a coin chute 22, the lip 15 bearing 80 the rest 20 forming one edge wall of this coin chute. The coin receiving foot 12 is slotted for the reception of a coin, as shown in Fig. 1 of the drawing, and has a thrust supporting side 23 which is wider than the 85 opposite side, extending above the upper edge of the latter, and which supports the coin against the thrust of the package and thus prevents the coin from becoming tipped so that it might pass underneath the package and thus not effect its removal. This 90 coin receiving foot 12 is so located in the normal position of the vending lever 6 that the slot will underlie the chute 22 and a coin passed into the coin slot 11 will be directed to the slot in the vending lever resting upon a ledge 24, notches 25 in which will prevent backward movement of the coin and lever after they have been once moved forward.

A delivery opening 27 is formed in the side of the casing 5 and a trap 26 is so located that it will guard the egress opening 16 against tampering as by means of instruments inserted through the egress and delivery openings. This trap is preferably pivoted as at 28 and it has a counterpoise arm 29 which serves to hold the trap normally in its closed position. When a package is moved from the receiver, as shown in 105 dotted outlines in Fig. 1, the trap will serve as a rest for the package which, it will be 110

noted, is not moved to such an extent that it will drop out of the opening 27, but is retained therein so that it may be easily removed by the purchaser and without falling to the floor. Means are provided for determining the extent of movement of the vending lever 6, and this may consist of the shelf 17 against which the coin strikes or the counterpoise 29 which will directly engage the coin receiving foot 12 and thus determine the movement of the lever.

It will be noted that the connections of the vending and coin levers causes the guard 9 to cover the slot 11 at the time the article is ejected from the receiver. In connection with this a stop 30 rests upon the pile of packages within the receiver with a stop pin 31 projecting from the under side. This stop will move downward with the packages, and when the last package has been removed the stop will occupy its place, the pin 31 resting in front of the coin receiving foot and holding the parts, as shown in dotted outline in Fig. 1, with the guard 9 completely closing the coin slot 11.

It will be noted that when the door 13 is removed all of the parts to which access may be had in supplying the machine are removed with the door, thus causing the device to be extremely convenient for the purpose of filling. The structure is such that it is of minimum size thus readily adapted for use on theater chairs and like places and the lever 6 projecting from the top near the back is in such position that it will not readily catch upon clothing or the like.

It will be noted that the wall 14 constituting one wall of the receptacle and also of the coin chute is longer than the opposite wall 14, the distance from the lip 20 to the lower edge of the longer wall in fact being less than the thickness of one of the packages. This is for the purpose of preventing a package being pushed backward and into the coin chute in which position it would intercept a coin and prevent operation of the device.

While I have shown and described herein a preferred form of construction of device embodying my ideas, this may be departed from to a greater or lesser extent without avoiding the invention which, therefore, is not limited to the exact construction herein shown and described.

55 I claim—

1. In a vending receptacle, a case having an opening at its front and also having a coin slot and a delivery opening in its wall, a door removably secured to close the opening in the front of the casing, walls projecting from the inner surface of the door in parallel relation, two of which form a package receiver and one in connection with the third forming a coin chute, said chute being positioned, when the door is in place, to un-

derlie the coin slot and one of said walls having an opening to register with said delivery opening when the door is in position, means for supporting articles in the package receiver, and means for ejecting articles 70 therefrom.

2. In a vending receptacle, a casing having an opening at its front and also having a coin slot and a delivery opening in its walls, a door removably secured to close the opening in the front of the casing, walls projecting from the inner face of the door in parallel relation, two forming the walls of a package receiver and the third in connection with one of the other walls forming a 80 coin chute positioned, when the door is in place, underneath the coin slot, one of said walls having an egress opening registering, when the door is in position, with said delivery opening, means for supporting articles in the chute, and a lever having a coin receiving slot located, in the normal position of the lever, directly underneath said coin chute.

3. In a vending receptacle, a casing having an opening at its front and also having a coin slot and a delivery opening, a vending lever pivotally mounted at the back of the casing, a guard operatively connected with the vending lever to close said slot, a door 95 to close the opening in the front of the casing, walls projecting from the door in parallel relation, two of which form a package receiver and the third in connection with one of the other two forming a coin chute 100 positioned, when the door is in place, directly underneath the coin slot and directly overlying the vending lever, another of said walls having an egress opening registering with said delivery opening, means for securing the door in position, and means for operating the lever.

4. In a vending receptacle, a casing having an opening at its front and also having a coin slot and a delivery opening in its 110 walls, a door removably secured to close the opening in the front of the casing, a vending lever pivotally mounted on the inside of the back wall of the casing, a coin receiving foot projecting from said lever, walls projecting from said door in parallel relation forming a package receiver and one of said walls in connection with another forming a coin slot with its mouth located under said coin slot and its discharge end over said coin receiving foot, one of said walls having an opening registering with the delivery opening in the casing, means for securing the door in place, and means for operating the lever.

5. In a vending receptacle, a casing having an opening at its front and also having a coin slot and a delivery opening in its walls, a door removably secured to close the opening in the front of the casing, a vend-

- ing lever pivotally mounted on the inside of the back wall of the casing and projecting through the end thereof to swing on a plane parallel with the plane of said cover, 5 a coin receiving foot projecting from said lever, walls projecting from said door in parallel relation, forming a package receiver and one of said walls in connection with another forming a coin chute with its 10 mouth located under said coin slot and its discharge end over said coin foot, one of said walls having an opening registering with the delivery opening in the casing, means for securing the door in place, and 15 means for operating the lever.
6. In a vending receptacle, a casing having an opening at its front and also having a coin slot and a delivery opening in its wall, a door removably secured to close the 20 opening in the front of the casing, a package receiver secured to said door and including walls arranged in parallel relation one of which forms the wall of a coin chute, the coin chute including another wall to complete 25 its construction and positioned when the door is in place to underlie the coin slot, a lever having a slot to receive a coin from said chute in a position to receive packages from said receiver, and means for retaining 30 a package in position with its edge projecting from said delivery opening after action of the coin upon the package.
7. In a vending receptacle, a casing, a package receiver located within the casing, 35 a vending lever pivotally mounted within the casing and having a coin receiving foot located at an angle thereto, means for delivering a coin to said foot, a shelf extending across one side of the bottom of the receiver to form a rest for the package and having a prong extending in the direction of movement of travel of the coin, said prong forming a guide for the coin and said shelf being located in the path of movement of a 45 coin to constitute a stop therefor, and means for operating the vending lever.
8. In a vending receptacle, a casing having an opening at its front and also having a coin slot and a delivery opening in its 50 walls, a door removably secured to close the opening in the front of the casing, a package receiver secured to said door and having an opening registering with said delivery opening when the door is in position, a 55 coin chute secured to said door and registering with said coin slot when the door is in position, a vending lever pivotally mounted at the back of the casing and having a coin receiving foot underlying said coin chute 60 when the door is in position, and means for operating the lever.
9. In a vending receptacle, a casing having an opening at its front and also having
- a coin slot and a delivery opening in its walls, a door removably secured to close the 65 opening in the front of the casing, a package receiver secured to said door and having an opening registering with said delivery opening when the door is in position, a coin chute secured to said door and registering 70 with said coin slot when the door is in position, means to receive said coin and carry it against the packages in said receiver, and means for retaining a package with its end projecting out of the delivery opening after 75 action on the package by a coin.
10. In a vending receptacle, a casing having an opening at its front and also having a coin slot and a delivery opening in its wall, means for supporting articles in said 80 receptacle, a coin lever movably mounted in the receptacle and having means to receive a coin and to move it against the article in the receptacle, means connected with said lever to close the coin slot in the movements of the lever, and means for retaining the lever in its abnormal position when the last package has been removed from the receptacle.
11. In a vending receptacle, a plate 90 arranged to be secured to a chair or like support, a coin lever having means to receive a coin and move it against an article in a receptacle, walls projecting in parallel relation two of which form a package receptacle and the third in connection with one of the other walls forming a coin chute positioned to overlie said coin receiving means in the coin lever, one of said walls having an egress opening, means for supporting articles in the receptacle in the path of movement of a coin, and a casing inclosing said parts and having a delivery opening registering with the egress opening in 95 said wall.
12. In a vending receptacle, a plate 100 arranged to be secured to a chair or like support, a vending lever pivotally mounted on said plate and having means to receive a coin and move it against an article in a 110 receptacle, a cover plate having walls projecting therefrom in parallel relation, two forming a package receptacle and a third in connection with one of the other walls forming a coin chute overlying the coin receiving 115 means in said vending lever and one of said walls having an egress opening, means for supporting articles in the receptacle, a casing to inclose the package receptacle, said casing having a delivery opening in its wall, 120 and means for securing the cover plate in position.

HARRY H. GOLDSTEIN.
